FIG. 1.

FIG. 2.

FIG. 3.

FIG. 4.

FIG. 5.

UNITED STATES PATENT OFFICE.

HENRY CONRAD BRAMER, OF CHESWICK, PENNSYLVANIA.

REAMER.

SPECIFICATION forming part of Letters Patent No. 783,816, dated February 28, 1905.

Application filed October 31, 1904. Serial No. 230,727.

To all whom it may concern:

Be it known that I, HENRY CONRAD BRAMER, a citizen of the United States, and a resident of Cheswick, in the county of Allegheny and State of Pennsylvania, have invented a new and Improved Reamer, of which the following is a full, clear, and exact description.

This invention relates to reamers; and it consists in the construction and combination 10 of parts hereinafter described and claimed.

In mining operations where holes are bored for the purpose of blasting some of the efficiency of the blast is lost by the escape of the gases at the time of the explosion through the 15 opening leading to the surface. It has been sought to overcome this difficulty by enlarging the bore of the hole at the bottom thereof at the point where the explosion takes place, the purpose being to afford a relatively 20 restricted outlet, which conduces toward a more complete inclosure of the gases after the explosion.

The object of this invention is to produce a device of simple construction which will operate 25 in connection with an ordinary drill or auger for the purpose of enlarging an opening or hole produced by the drill.

In its construction the device comprises a chuck in which a pair of oppositely-disposed 30 cutters or bits are pivoted. As the device is advanced the points of these bits diverge, so as to cut an enlarged chamber.

The special object of this invention is to simplify the construction and means for 35 mounting the bits in the chuck and limiting the diverging movement thereof.

Reference is to be had to the accompanying drawings, forming a part of this specification, in which similar characters of reference indicate 40 corresponding parts in all the figures.

Figure 1 is a perspective of the device, representing the same as detached from the end of a drill. Fig. 2 is a section supposed to be taken through a vein and representing an ordinary 45 drill in process of forming a hole for the blast charge. Fig. 3 is a view similar to Fig. 2, but representing a drill provided with my device, showing the same entering a hole for the purpose of reaming or enlarging the 50 same at its base. Fig. 4 is a view similar to

Figs. 2 and 3, but representing my device in operation and illustrating the enlarged chamber which it forms; and Fig. 5 is a longitudinal central section taken through the device, representing the bits in their normal closed position in full lines, the bits being represented in their open or divergent position in dotted lines.

Referring more particularly to the parts, 1 represents the body or chuck of the reamer. 60 It consists, preferably, of a thick flat plate, which is cut away centrally on its opposite edges, so as to form a pair of recesses or throats 2 and 3. In the throat 2, near the outer edge 4 thereof, a pair of oppositely-disposed cutters or bits 5 are pivotally mounted upon pins 6, as indicated most clearly in Fig. 5. The bits 5 are preferably of substantially triangular form, as indicated in Fig. 5, and their outer edges 7 are normally disposed substantially parallel with the side edges 8 of the body 1, as shown. The outer extremities of the bits terminate in sharp points 9, and the inner or adjacent edges 10 of the bits are preferably curved and converge toward each other, 75 as indicated, passing into the space between the pivot-pins 6. From a point 11 lying substantially upon a line joining the pivots 6 the rear edges or cheeks 12 of the bits diverge rearwardly, and these edges 12 meet the aforesaid edges 7 in points 13, as indicated. The edges 10 are preferably beveled and disposed in an opposite relation, the purpose of this bevel being to facilitate the cutting operation at the points 9. The bits 5 normally occupy 85 substantially the position in which they are shown in full lines in Fig. 5. The points 9 are prevented from approaching more nearly to each other by means of projections or stops 14, which project into the throat 2, as will be 90 readily understood.

On the central longitudinal axis of the body 1 a main stop pin or stud 15 is located, and this stop is adapted to coöperate with the bits in order to limit their movement and to insure that the points 9 will dispose themselves at the same distance from the axis when they have diverged to their fullest extent. In the edges 12 at suitable points the same are provided with recesses 16, which receive said 100

stop-pin 15 in the manner indicated in dotted lines in Fig. 5, at the same time allowing the faces or edges 12 to come against each other. In this way while the stud 15 does operate as a stop it is substantially relieved of all pressure tending to break it off, because the forces on the opposite sides of the same equalize each other. In this manner the bits are made to arrest their own movement and constitute opposed stops for each other.

When operating with the device, a vein 17, such as that indicated in Fig. 2, would be bored into with a drill 18, so as to form an opening or hole 19. Drills used for this purpose usually have oppositely-disposed separated points 20, with diverging cutting edges 21. As these points 20 rotate they of course operate to form a conical base or nipple 22 at the bottom of the opening. The presence of this base or nipple 22 is utilized to cause the bits 5 of my device to expand. The reamer is to be attached to the extremity of the drill and introduced into the opening in the manner indicated in Fig. 3, it being understood that when the bits are in their contracted or folded position they may be readily introduced into the opening. When the reamer reaches the bottom of the opening and the drill 18 is rotated, the pressure of the base 22 between the bits at the edges 10 operates to force them outwardly, so that in their rotation they will form an enlarged chamber 23, such as that indicated in Fig. 4. The diameter of this chamber is of course determined by the limit to which the points 9 of the bits may diverge. When the chamber 23 has been given sufficient depth, the drill and the reamer may be readily withdrawn from the opening, as the bits will easily return to their normal folded relation.

The end of the drill 18 is preferably attached to the body 1 of the reamer by inserting its end in the throat 3 aforesaid and securing the same therein by means of suitable fastening devices, such as the screws 24, seating in suitable openings 25 in the body.

While I prefer to make the body 1 of the device of substantially rectangular form, as shown, in practice, where found desirable, this body could be made of cylindrical form, and this latter form will usually be adopted where other means were not provided for insuring a proper centering of the device in the drill-hole. Of course such means are unneces-

sary with the form of drill shown, as the body of the drill assists in centering the device.

Having thus described my invention, I claim as new and desire to secure by Letters Patent—

1. In a device of the class described, in combination, a body presenting a throat, pivot pins disposed across said throat, a pair of oppositely-disposed bits pivotally mounted on said pins and in said throat and having points adapted to diverge as said bits rotate upon their pivots, said bits having rear faces adapted to abut substantially upon the central axis of said body, and a stud upon said central axis and limiting the inward movement of said faces.

2. In a device of the class described, in combination, a body presenting a throat, a pair of oppositely-disposed bits mounted upon pivots in said throat, said bits having points adapted to diverge as said bits rotate upon said pivots, said bits further having cutting edges converging from the points thereof into the space between said pivots and rear faces formed on lines passing from a point lying substantially centrally between said pivots, said faces having oppositely-disposed recesses, a stud mounted in said throat upon the central axis of said body and adapted to engage said recesses, and a pair of stops near the outer edges of said throat and limiting the inward movement of said points.

3. In a device of the class described, in combination, a body presenting a throat, a pair of oppositely-disposed bits mounted upon pivots in said throat, said bits having points adapted to diverge as said bits rotate upon said pivots, said bits further having cutting edges converging from the points thereof into the space between said pivots and rear faces formed on lines passing from a point lying substantially centrally between said pivots, said faces having oppositely-disposed recesses, a stud mounted in said throat upon the central axis of said body and adapted to engage said recesses, a pair of stops near the outer edges of said throat and limiting the inward movement of said points, and means for attaching said body to a drill.

In testimony whereof I have signed my name to this specification in the presence of two subscribing witnesses.

HENRY CONRAD BRAMER.
